(57) **CLAIM**

The ornamental design for a garment, as shown and described.

DESCRIPTION

FIG. 1 is a front perspective view of a garment showing my new design;

FIG. 2 is a front view thereof;

FIG. 3 is a rear view thereof;

FIG. 4 is a left side view thereof;

FIG. 5 is a right side view thereof;

FIG. 6 is an enlarged view of the encircled portion labeled "6" in FIG. 1;

FIG. 7 is an enlarged view of the encircled portion labeled "7" in FIG. 5;

FIG. 8 is a front perspective view of a garment showing my new design in an alternative embodiment;

FIG. 9 is a front view thereof;

FIG. 10 is a rear view thereof;

FIG. 11 is a left side view thereof; and,

FIG. 12 is a right side view thereof.

The broken lines within the shaded area represent stitching and form no part of the claimed design. The broken lines depicting the icons on the controller form no part of the claimed design. The broken lines immediately adjacent to the shaded areas represent the bounds of the claimed design and form no part thereof. The broken lines depicting the remainder of the garment form no part of the claimed design.

1 Claim, 12 Drawing Sheets
